BIASED CANOPY FOR VENDING TRAILERS
Socrates J. Schantz, Box 134, Marine, Ill. 62061
Filed Oct. 23, 1965, Ser. No. 503,338
8 Claims. (Cl. 160—62)

ABSTRACT OF THE DISCLOSURE

A canopy for use with vending trailers and the like which is spring loaded for easy raising from a locked position to a raised and assembled position. The canopy has a roof member hingedly connected to a trailer frame and hinged front and side wing members. The biasing is effected by connecting a spring from the frame to the side wing members to urge the canopy, including the roof, front and side wing members, to raised and assembled positions.

This invention finds particular usefulness in providing a canopy for small vending stands which are transported from one location to another. Such vending stands may be mounted upon a trailer in well known fashion which, because of their mobility, are adapted to service any desired locality such as in the neighborhood of schools, athletic contests, etc., where people congregate and patronize the stand. Such stands conventionally vend hot dogs, soft drinks, ice cream and the like. In the past, it has been conventional to vend from an opened window at one side of the stand. It is quite desirable to provide a top canopy or roof to protect the customer from the direct rays of sunlight or possible inclement weather. Also, through the use of a projecting roof the interior of the stand may be protected against the hazards of weather.

Summary of the invention

This invention provides a folding canopy which can be easily set up to the assembled position in a matter of minutes after the stand has been located in the desired position. The canopy is of a rectangular configuration and has what may be termed an overlying roof portion and side or wing members, which aid in supporting the roof member. The canopy of this invention is an improvement over the folding canopy shown in my United States Patent No. 2,896,706.

As a special feature of this invention, the canopy can have the front and side wing members, which are bordered at their peripheral sides of the roof member, erected by an operator as soon as the canopy has been unlocked. With this pre-assembly of the wing members, the canopy is spring loaded or biased, such that it may be very simply raised to the assembled position and engaged in a locking position. Thus, the erection is very simple and can be accomplished by women without the requirement of any special skill or effort in the way of manual labor.

The construction of the vending stand canopy is simple in nature and rugged so that it will readily withstand the rigors of transportation. As a very desirable feature, it may be knocked down or collapsed from the canopy position to the window boarding up position in a very short period of time without the requirement of any special tools. Conversely, the canopy may be assembled to the final canopy position from the boarded up position in a very short period of time by a reversal of the operation.

The above features are objects of this invention and further objects will appear in the detailed description which follows and will otherwise be apparent to those skilled in the art.

For the purpose of illustration of this invention, there is shown in the accompanying drawings a preferred embodiment thereof. It is to be understood that these draw-

2

ings are for the purpose of example only, and that the invention is not limited thereto.

In the drawings:

FIGURE 1 is a view of the canopy in the closed or down position taken in front elevation;

FIGURE 2 is a view similar to FIGURE 1 but taken from the right side thereof;

FIGURE 3 is a view in front elevation showing the canopy in the raised and fully assembled position;

FIGURE 4 is a view in rear elevation of the canopy in the closed or down position;

FIGURE 5 is a fragmentary view in rear elevation showing the canopy in the raised position;

FIGURE 6 is an enlarged view in side elevation taken from the right side of the canopy showing the raised position;

FIGURE 7 is an enlarged view in section taken on the line 7—7 of FIGURE 6;

FIGURE 8 is an enlarged view taken on the line 8—8 of FIGURE 1;

FIGURE 9 is an enlarged view taken on the line 9—9 of FIGURE 1;

FIGURE 10 is an enlarged fragmentary top plan view of the right end portion of the canopy in the erected position;

FIGURE 11 is an enlarged view in section taken on the line 11—11 of FIGURE 10;

FIGURE 12 is an enlarged fragmentary view in elevation taken from the right side of the canopy showing an intermediate stage in the erection;

FIGURE 13 is a fragmentary view taken similarly to FIGURE 12 but showing the disassembly of the front wing member from the right side wing member;

FIGURE 14 is an enlarged plan view of a lock for locking the side wing members to the canopy in the disassembled position;

FIGURE 15 is an enlarged top plan view partially in section showing a lock for the side wing members in the disassembled position; and

FIGURE 16 is an enlarged view of the wing nut used in locking the front wing member to the canopy stand in the disassembled position.

Referring now to the drawings, the folding canopy of this invention is generally indicated by the reference numeral 20 in FIGURES 1, 2, 3, 4, 10, 11 and 12. It is supported upon a vending stand 22 having a window opening 23, and it will be understood that the stand may be part of a trailer or stationary as desired. The stand 22 forms a frame around the window, and it will be understood that one canopy or several may be used around the stand. The canopy is comprised of a roof member 24 and three wing members, namely front wing member 26, left side wing member 28, and right side wing member 30. Biasing springs 32 and 34 connected at the top to the vending stand and at their lower ends of the side wing members provide for biasing of the canopy to the raised or assembled position for ease in erection, and also aid in unfolding the side wing members which are biased toward the assembled position by the springs.

The roof member, as best shown in FIGURES 4 and 8, is connected to a top cross piece 35 of the vending stand by three hinges 36. The roof member further supports the front wing member 26 by means of a hinge 38, which extends along the length of the roof member.

Latch members 40 are supported upon the roof member, as shown in FIGURE 1 and FIGURE 9, to hold the side wing members 28 and 30 in the knocked down position shown in FIGURE 1. The latch members 40 are more fully shown in FIGURE 14, as comprising a base member 42, which is mounted to a longitudinally extending rib 44 on the roof member, and a latch element 46

connected by a latch hinge 48 in hinged relation to the roof. The latch element 46 may be swung from the latched position shown in FIGURE 1 counterclockwise to disengage the left wing member 28 and in a counterclockwise position to disengage the right side wing member 30.

A second latch means 50 is supported on the cross piece 35 of the vending stand to hold the back portion of the wing members in locked position. These latch members are best shown in FIGURE 1 and FIGURE 8, and are hingedly connected by a hinge element 52 to the vending stand cross piece, while a latch hook portion 54 engages the wing member through a flange element 56 at the rear or back of the wing member.

The front wing member 26 is best shown in FIGURES 1, 4, 10 and 11. As there shown, it is provided with a thumb screw 60 connected to a lock plate 62 at the rear of the wing member, such that the lock plate 62 can be engaged with vertical frame members 64 of the vending stand to lock the canopy against it in the disassembled or knocked down position.

The front wing member 26 is further provided with front flange element 66 and side flanged elements 68 and 70. The side elements 68 and 70 provide for engagement with the side wing members to hold the wing members in assembled position in rigid connection.

The two side wing members 28 and 30 are identical in construction except for reversal of their parts and, accordingly, only the right side wing member 30 will be described. It is best shown in FIGURES 1, 6, 10, 11 and 12. As there shown, it is connected by a hinge 72 extending along its length to the side of the roof member. It is further provided with a flange 74, which extends across the width of the wing member, and a second flange 76, which extends across the length of the wing member. These two flanges, as shown in FIGURE 10, are spaced apart from one another to provide an opening 78, which receives the flanges of the front wing member in the assembled position. The flange 76 further serves to protect the spring 34 in the canopy assembled position, and, additionally, is provided with a hooked portion 56, as shown in FIGURE 10. The hooked portion 56 is engageable with a hook 82 fixed to the cross piece 34 of the vending stand to lock the canopy in the assembled position.

Use

The canopy is shown in the knocked down or disassembled position in FIGURES 1, 2 and 4. From this position it can be very simply erected to the canopy raised position, and, once raised, then disassembled and returned to the canopy knocked down position. This is of great advantage in the set up of trailer stands and other operations requiring an easily assembled canopy.

For the erection of the canopy from the knocked down position, the thumb screws 60 are first loosened. Once this disengagement of the front wing member with the vending stand has been accomplished, the front wing member is raised to the vertical position with respect to the roof member 24. Then the latch members 50 are disengaged from the back ends of the side wing members. Likewise the latch members 40 are disengaged from the front portions of the wing members and the wing members, which are biased by the springs, are then fully raised to the vertical position for engagement at their front ends with the front wing member. All this can be done by an operator standing upon the ground. It will be understood that in the foregoing operation, where desired, the side wing members may be first disengaged and then the front wing member may be disengaged and the various members then may be connected together. Once the disengagement of the wing members has been accomplished from their locked positions and connected to one another, the canopy is raised to the position shown in FIGURE 12 by the biasing spring, and a very simple effort by the user completes the raising and erection of the

canopy to the position shown in the fully erected position for FIGURES 3, 10 and 11. Once raised, the back ends of the wing members are bent slightly toward one another to engage the locking flanges 56 with the locks 82. Once so engaged, the canopy is held firmly in position and is ready for use.

For disassembly to the knocked down position, the reverse operation is carried out. Thus, the locking flanges 56 and the wing members are disengaged from the locks 82. Once this has been accomplished, the canopy is brought down and the side wing members are disengaged from the front wing member. The front wing member is then locked against the canopy stand by tightening the thumb screw to engage the lock plate 62 with the vending stand. The wing members are then folded over against the roof member to the position shown in FIGURE 1, and the latch members 40 and 50 are engaged with the front and back portions of the wing members, respectively, to hold the wing members in place.

When the canopy is collapsed and knocked down, it firmly closes the opening in the vending stand and is securely locked in place. No tools of any type are required to bring about the collapsing and locking of the component parts, or to provide for the erection or assembly of the canopy.

Various changes and modifications may be made in the canopy of this invention as will be readily apparent to those skilled in the art. Such changes and modifications are within the scope and teaching of this invention as defined by the claims appended hereto.

What is claimed is:

1. A collapsible canopy adapted to be assembled from a collapsed position against a vertical frame to an assembled and raised horizontal position, said canopy comprising a roof member having hinge means connecting it to the frame, front and side wing members hingedly connected to the front and sides of the roof member, and spring biasing means connecting the canopy to the frame to assist in assembly, the spring biasing means comprising a spring connected at one end to the frame above the roof hinge means and at the other end to one of the side wing members to provide a biasing means on the side wing members to urge the canopy to a raised position and the side wing members to the assembled position.
2. The canopy of claim 1 in which said front and side wing members are provided with flange means to connect each of the side wing members to the front wing member to hold the canopy in rigid relation.
3. The canopy of claim 1 in which said front wing member in the disassembled position is foldable to a position in the same plane as the roof member and has means for locking it to the frame.
4. The canopy of claim 1 in which said roof member has latch means in the disassembled position engageable with the side wing members to lock them flat against the roof member.
5. The canopy of claim 1 in which there is a locking means for the canopy in the assembled position connecting a lock element of the side wing members to lock elements fixed to the frame.
6. The canopy of claim 1 in which said front and side wing members are provided with flange means to connect each of the side wing members to the front wing member to hold the canopy in rigid relation, said front wing member in the disassembled position being foldable to a position in the same plane as the roof member and having means for locking it to the frame, said side wing members having latch means in the disassembled position engageable with the side wing members to lock them flat against the roof member.
7. The canopy of claim 1 in which said front and side wing members are provided with flange means to connect each of the side wing members to the front wing member to hold the canopy in rigid relation, and locking means for the canopy in the assembled position connecting a lock

element of the side wing members to lock elements fixed to the frame.

8. The canopy of claim 1 in which said front and side wing members are provided with flange means to connect each of the side wing members to the front wing member to hold the canopy in rigid relation, said front wing member in the disassembled position being foldable to a position in the same plane as the roof member and having means for locking it to the frame, said side wing members having latch means in the disassembled position engageable with the side wing members to lock them flat against the roof member, and locking means for the canopy in the assembled position connecting a lock element of the side wing members to lock elements fixed to

the frame, and said spring biasing means comprising a spring connected at one end to the frame above the roof hinge means and at the other end to one of the side wing members.
